UNITED STATES PATENT OFFICE.

ROBERT MILNE, OF ROCKFORD, ILLINOIS, ASSIGNOR TO B. F. BARNES COMPANY, A CORPORATION OF ILLINOIS.

ROD-Straightening Mechanism.

No. 903,999.

Specification of Letters Patent.

Patented Nov. 17, 1908.

Application filed November 25, 1907. Serial No. 403,668.

To all whom it may concern:

Be it known that I, ROBERT MILNE, a citizen of the United States, residing at Rockford, in the county of Winnebago and State 5 of Illinois, have invented certain new and useful Improvements in Rod-Straightening Mechanism, of which the following is a specification.

This invention relates to mechanism for 10 straightening rods for machine work which ordinarily have slight bends or deflections when delivered to the machine shop.

The object of the invention is to provide a 15 simple, convenient and easily manipulated straightening head adapted to exert a high degree of pressure on any defective portion of a rod and adapted to be moved without difficulty to any position required in varying length.

20 The invention further relates to the means for imparting revolution to the rod from time to time during the straightening operation in order to test the same; and to the means provided for automatically raising 25 the rod from a position of rest and thereafter imparting the necessary rotation thereto.

The invention consists in the features of 30 construction and combination of parts hereinafter described and claimed.

In the drawings Figure 1 is a side elevation of the entire device; Fig. 2 a sectional elevation of the adjustable bearing head and movable frame; Fig. 3 a cross sectional elevation of the cone bearing for the work and the mounting therefor; Fig. 4 a plan view of the same; Fig. 5 a plan view of the hand wheel and ratchet; Fig. 6 a sectional elevation of the friction clutch; and Fig. 7 a cross 40 sectional view taken through line 7-7 of Fig. 6 looking in the direction of the arrow.

The straightening mechanism as a whole is mounted upon a table 8 having legs 9 of sufficient length to raise the work to a convenient level for manipulation. The table is 45 provided with a top plate 10, the edges of which project beyond the remainder of the table sufficiently to provide overhanging guideways which are parallel with one another and extend from end to end of the table. The table is provided in its center with a longitudinally extending slot 11 of inverted T formation, which slot opens into a longitudinally extending channel 12 in the center of the table surface. The slot and chan-

nel furnish a guideway for the adjustment of the traveling compressor frame and the adjustable bearing to be hereinafter described.

At one end of the table are located outer 60 and inner journal boxes 12 and 13, respectively, which furnish the bearing for a revoluble shaft 14, having on its end a cone pulley 15. From the inner end of the shaft projects a cone stud 16, shown in Fig. 6, 65 which stud projects inwardly beyond the inner journal box 13 and co-operates with a movable clutch disk 17, which is slidably mounted upon two pins or studs 18, which inwardly project from the face of the shaft 70 head 18^a and are slidably mounted within recesses 19 in the clutch disk. The pins are supplemented by two coiled springs 20, the ends of which are entered into recesses 21 and 22 in the inner end of the shaft head and 75 the rear face of the clutch disk respectively, the guideways and springs being alternately arranged with respect to one another. The acting face of the friction disk is covered by a leather washer 23 which gives the required 80 friction in imparting rotation to the work. The friction clutch co-operates with a cone bearing rod 24 located at the opposite end of the table and mounted within a sleeve 25 which, as shown in Fig. 3, is split on one side 85 and is provided with outwardly extending ears 26. The ears are adapted to be clamped together by means of a screw bolt 27 which can be tightened up by a handle 28 as shown in Fig. 3. This enables the cone bearing rod 90 to be adjusted and thereafter clamped in different positions. The rear end 29 of the bearing rod is engaged by a slotted lever 30 the end of which is pivoted to an arm 31 rearwardly and laterally projecting from the 95 farther or rear side of the split sleeve, which arrangement permits manipulation of the bearing rod. The sleeve is supported upon lugs 32 which are connected with a bed plate 33 provided with a tongue 34 which enters 100 the channel 12 in the surface of the table and permits the bed plate to be moved to different positions of adjustment. The bed plate has entered therethrough a bolt 35 the head of which is entered into the inverted T slot 105 in the table and is adapted to be clamped against the overhanging walls thereof by means of a handle 36.

The work 37 is journaled at its rear end upon the cone bearing, and when not being 110

rotated rests upon a pair of blocks 38 each of which is provided with a concave opening 39 in its upper face, and is provided with a tongue 40 adapted to enter the groove in 5 the table. The size of the blocks is such that they will support the work, when in a state of rest, at a position slightly below the apex of the cone stud which revolves with the shaft and with the friction clutch member 10 thereon.

The top plate of the table serves as a track or guideway for a traveling frame or mounting 41 of inverted U shape, which is provided at its lower end with inturned fingers 42 15 which engage the edge of the table top and serve to position the frame or mounting during its travel along the table. Above the fingers, on each side of the mounting or frame, are a pair of lugs 43 each of which has pivoted thereto a roller 44, which rollers rest upon the top of the table adjacent to the edge thereof and provide an easy means for moving the frame or mounting from one position 20 to another. The U shaped frame has entered through its head 45 a screw 46 provided on its upper end with a hand wheel 47, which hand wheel is provided with a hub 48 upon the face of which are located a plurality of lugs 49. In adjusting the screw 25 30 the hand wheel can be used, or if additional power is required, a hand lever 50 provided with a dog 51 can be employed, which lever, being longer than the radius of the wheel, affords increased leverage in case the wheel 35 40 prove insufficient to afford the necessary power. The lever is pivoted at its inner end to a stud 52 which upwardly projects from and is rotatably mounted in the end of the screw 46, which arrangement permits the 45 50 lever to be turned independently of the screw and to impart rotation thereto in one direction only through the action of the dog against the lugs on the face of the hub 48. The adjusting screw is screw threaded 55 60 through the head 45, but travels freely through a collar 53 through which it passes and which is provided with a slot 54 which co-operates with a spline or key 55 slideable within the slot, which arrangement imparts 65 70 rotation to the collar but permits the adjusting screw to feed forward and back therethrough as the adjusting screw is moved. The collar is preferably provided on its periphery with marks or graduations 56, which 75 80 serve to indicate the degree of movement given to the adjusting screw by the rotation thereof.

The adjusting screw has, on its inner end, a bearing head 57 in which the smooth stub end 58 of the screw is entered, being held therein by a suitable device, as for instance, a split ring 59 the members of which are held in contracted position by set screws 60 or other suitable means. In order to pre-

vent the rotation of the bearing head a screw 65 stud 61 is provided, the head of which is entered between guide flanges 62 on the inner face of one of the arms of the mounting or frame, as shown in Fig. 1. The graduated collar 53 is held in position on top of the 70 mounting or frame by means of a yoke plate 63 which is fastened to the frame or mounting by means of a pair of bolts 64.

In use, when it is desired to straighten a rod or similar piece of work, the same is 75 laid in position on the table resting upon a pair of supporting blocks 38, which are moved to suitable position to support the rod on either side of the bent portion which it is desired to straighten. When supported 80 in this manner, the forward end of the rod will be closely adjacent to the cone stud of the clutch member, and the center of the rod, in which a cone slot has been drilled, will be 85 slightly below and in vertical alinement with the apex of the cone stud. These positions can be obtained by adjusting the cone bearing at the opposite end of the rod to suitable position to hold the work as above indicated. Power being applied to the shaft, 90 the cone stud and clutch member will be revolved with the shaft, the work remaining 95 stationary meanwhile. When it is desired to revolve the work the lever 30 can be drawn forward, which moves the cone bearing rod in its sleeve and forces the work against the friction clutch, thereby forcing the latter back and compressing the springs. This retraction of the friction clutch disk and leather facing forces the work against 100 the rapidly revolving cone stud which, when the clutch member is retracted and the work advanced, will engage the end of the work and center it by raising it slightly off of the bearing blocks. This raising will be accomplished by the action of the beveled cone surfaces so that no further adjustment is necessary to impart rotation to the work. With 105 the work thus revolving a mark can be made with a piece of chalk, or similar marking substance at the intended point, which mark should be made with the chalk held rigidly in the intended position. If the mark is broken at any point, such break will indicate a depression or bend in the work after 110 which the traveling frame or mounting can be moved to a position directly above the defective point in the work and pressure applied thereto by revolving the screw. Pressure can be centered between any desired 115 points by increasing or decreasing the distance spanned by the work between the two blocks, thereby accommodating bends of greater or less length or degree. The graduations on the collar enable the operator to 120 judge of the amount of movement of the screw and the proportionate pressure applied thereby. After pressure has been ap-

plied in the manner indicated, additional tests can be made with the chalk marker until the work is exactly straightened.

By locating the parts in the manner indicated the compression screw can be quickly adjusted to any desired position so that there will be no necessity for moving the work itself which always remains suitably positioned to be revolved at the will of the operator whereby repeated tests can be made without additional manipulation or readjustment.

What I regard as new and desire to secure by Letters Patent is:

- 15 1. In a straightening machine, the combination of a bearing adapted to engage one end of the work, means for moving the bearing to give a longitudinal movement to the work, a friction clutch for the opposite end 20 of the work provided with a member adapted to automatically lift and center the work when the latter is longitudinally moved by the movement of the bearing at the opposite end of the work, a block upon which the 25 work is supported when at rest in a position below the position to which it is automatically raised by the centering member, and means for applying pressure to the work, substantially as described.
- 30 2. In a straightening machine, the combination of a bearing adapted to engage one end of the work, means for moving the bearing to give a longitudinal movement to the work, a friction clutch for the opposite end 35 of the work provided with a member adapted to automatically lift and center the work when the latter is longitudinally moved by the movement of the bearing at the opposite end of the work, a block upon which the 40 work is supported when at rest in a position below the position to which it is automatically raised by the centering member, and means, longitudinally movable from end to end of the work, for applying pressure 45 thereto, substantially as described.
3. In a straightening machine, the combination of a bearing adapted to engage one end of the work, means for moving the bearing to give a longitudinal movement to the 50 work, a friction clutch for the opposite end of the work, provided with a cone member adapted to lift and center the work, a block upon which the work is supported, when at rest, in a position below the axis of the cone, 55 and means for applying pressure to the work, substantially as described.
4. In a straightening machine, the combination of a bearing adapted to engage one end of the work, means for moving the bearing to give a longitudinal movement to the work, a friction clutch for the opposite end 60 of the work, provided with a cone member adapted to lift and center the work, a block upon which the work is supported, when at rest, in a position below the axis of the cone, 65

and adjustable means for applying pressure to the work at a predetermined point, substantially as described.

5. In a straightening machine, the combination of a bearing adapted to engage one end of the work, means for moving the bearing to give a longitudinal movement to the work, a friction clutch for the opposite end of the work, provided with a cone member adapted to lift and center the work, a block 75 upon which the work is supported, when at rest, in a position below the axis of the cone, an adjustable screw member, provided at its lower end with a bearing head, a mounting for said screw member, and a track upon 80 which the mounting is adapted to run, substantially as described.

6. In a straightening machine, the combination of a bearing adapted to engage one end of the work, means for moving the bearing to give a longitudinal movement to the work, a friction clutch for the opposite end 85 of the work, provided with a cone member adapted to lift and center the work, a block upon which the work is supported, when at rest, in a position below the axis of the cone, an adjustable screw member, provided at its lower end with a bearing head, a mounting for said screw member, a track upon which 90 the mounting is adapted to run, and a hand wheel on the upper end of the adjustable screw, substantially as described.

7. In a straightening machine, the combination of a bearing adapted to engage one end of the work, means for moving the bearing to give a longitudinal movement to the work, a friction clutch for the opposite end 100 of the work, provided with a cone member adapted to lift and center the work, a block upon which the work is supported, when at rest, in a position below the axis of the cone, a mounting of inverted U-shape provided with wheels, a trackway along which said 105 wheels are adapted to roll, an adjusting screw entered through said mounting, and provided at its lower end with a bearing head and at its upper end with means for 110 imparting rotation thereto, substantially as described.

8. In a straightening machine, the combination of a bearing adapted to engage one end of the work, means for moving the bearing to give a longitudinal movement to the work, a friction clutch for the opposite end 115 of the work, provided with a cone member adapted to lift and center the work, a block upon which the work is supported, when at rest, in a position below the axis of the cone, a mounting of inverted U-shape provided with wheels, a trackway along which said 120 wheels are adapted to roll, an adjusting screw entered through said mounting, and provided at its lower end with a bearing head and at its upper end with means for 125 imparting rotation thereto, and a graduated 130

collar, revoluble with the hand wheel and adapted to indicate units of adjustment, substantially as described.

9. In a straightening machine, the combination of a supporting table, a bearing for one end of the work, comprising a bearing member adapted to engage the end of the work, and a mounting therefor permitting longitudinal adjustment, a clutch member 10 for the opposite end of the work, comprising a spring supported friction member adapted to bear against the end of the work, a cone member normally behind the frictional surface of the friction member and adapted to 15 be outwardly projected, with respect to said frictional surface, by the retraction of the latter, due to longitudinal movement imparted to the work by the movement of the end bearing, means for imparting rotation to 20 the friction clutch member, and adjustable means for exerting a straightening pressure on the work, substantially as described.

10. In a straightening machine, the combination of a supporting table, a bearing for 25 one end of the work, comprising a bearing member adapted to engage the end of the work, and a mounting therefor permitting longitudinal adjustment, a clutch member for the opposite end of the work, comprising 30 a spring supported friction member adapted to bear against the end of the work, a cone member normally behind the frictional surface of the friction member and adapted to be outwardly projected, with respect to said 35 frictional surface, by the retraction of the latter, due to longitudinal movement imparted to the work by the movement of the end bearing, means for imparting rotation to the friction clutch member, a screw member 40 provided with a head, adapted to exert a straightening pressure on the work, and a mounting of inverted U-shape adapted to travel along the table, through which mounting the adjusting screw is entered, substantially 45 as described.

11. In a straightening machine, the combination of a supporting table, a bearing for

one end of the work, comprising a bearing member adapted to engage the end of the work, and a mounting therefor permitting 50 longitudinal adjustment, a clutch member for the opposite end of the work, comprising a spring supported friction member adapted to bear against the end of the work, a cone member normally behind the frictional surface 55 of the friction member and adapted to be outwardly projected, with respect to said frictional surface, by the retraction of the latter, due to longitudinal movement imparted to the work by the movement of the end bearing, means for imparting rotation to 60 the friction clutch member, a screw member provided with a head adapted to exert a straightening pressure on the work, and a mounting of inverted U-shape adapted to 65 travel along the table, through which mounting the adjusting screw is entered, and a block for holding the work, when at rest, below the axial center of the cone member of the friction clutch, substantially as described. 70

12. In a straightening machine, the combination of a table, a bearing for one end of the work, comprising a rod having a cone at its inner end, and a mounting for said rod adapted to permit longitudinal adjustment, 75 a friction clutch adapted to engage the opposite end of the work and comprising a cone stud, a slidably mounted clutch disk surrounding said cone stud, and provided on its face with a friction disk adapted to engage 80 the end of the work, the clutch member being retractable to permit projection of the cone stud and contact thereof with the work, springs for normally holding the clutch disk in projected position, a shaft into which the 85 cone member is entered, means for imparting rotation to the shaft, and straightening means adapted to be adjusted to different positions with respect to the work, substantially as described.

ROBERT MILNE.
